STOVE PIPE-TENT POLE COMBINATION WITH SHIELD

Edward F. Campbell, Jeffersonville, Ind.

Application September 2, 1949, Serial No. 113,893

1 Claim. (Cl. 135—14)

(Granted under the act of March 3, 1883, as
amended April 30, 1928; 370 O. G. 757)

1

The invention described herein, if patented, may be manufactured and used by or for the Government for governmental purposes without the payment to me of any royalty thereon.

This invention relates to a tent of the type in which a stove may be installed and the stovepipe extends upwardly through an opening in the tent body.

A primary object of the invention resides in the provision of a stovepipe of sturdy construction which is supported directly on the ground or other foundation and thus provides an efficient construction from which the tent covering may be suspended.

Another object of the invention consists in providing such a stovepipe with a draft opening which may be suitably adjusted to properly control the fire in the stove.

A still further object of the invention resides in the provision of combined tent shield and attaching means which not only serves to space the tent fabric from the stovepipe but also provides a fastening means for connecting the upper edge of the fabric to the shield so that the entire load of the tent fabric may be supported by the shield which is, in turn, supported by the stovepipe.

Other objects and advantages of the invention will be apparent from the following description when considered in connection with the accompanying drawings in which,

Fig. 1 is an elevational view of the stovepipe showing a portion of a stove associated therewith, and indicating the upper portion of the tent fabric in dotted outlines;

Fig. 2 is a bottom plan view of the frustoconical shield;

Fig. 3 is a fragmentary sectional view through the shield and showing the connection between the latter and the tent body;

Fig. 4 is a fragmentary perspective view showing the connection between the shield and tent fabric;

Fig. 5 is a horizontal view taken on the line 5—5 of Figure 1, and looking in the direction of the arrows; and

Fig. 6 is a fragmentary longitudinal sectional view through one of the stovepipe joints.

As indicated hereinbefore, this invention has to do with the construction of a combined stovepipe and tent pole and to this end the structure includes a base plate 1 which is adapted to be located on the ground or other foundation and provided with a seat 2 for the reception of the lower end of the stovepipe which is indicated

generally by the numeral 3. In the present illustration the stovepipe is formed of a plurality of sections, five such sections being depicted in the illustration. The lowermost section is indicated by the numeral 4 and is provided with vertically extending guideways 5 for the reception of a slidably mounted arcuate plate 6 which serves to regulate the effective size of the opening 7, thereby varying the amount of atmospheric air passing into the stovepipe and consequently the force of the draft applied to the stove which is designated by the numeral 8.

A conduit 9 provides the necessary connection between the stove and the stovepipe 3. The lower end of the pipe section 4 may be spot welded or otherwise connected to the seat 2 of base plate 1 as indicated by the numeral 10 and the upper end of each of the several sections of the stovepipe may be necked-in as indicated by the numeral 11, or otherwise constructed so as to provide a shoulder such as indicated by the numeral 12, to form a seat for the lower end of the immediately adjacent upper section, thereby providing a sturdy and secure support for the several sections, which, as a stovepipe, serve to bear the entire load of the tent fabric.

The topmost section of the stovepipe is indicated by the numeral 13 and is likewise necked-in to provide a shoulder 12 to form a seat and support for a shield 14. This shield is of frustoconical shape and may be fabricated of any preferred metal or other non-inflammable material, and serves the dual function of spacing the upper portion of the tent fabric from the stovepipe and providing a support for a plurality of fastening elements for securing the upper edge of the tent fabric to the shield. In the present illustration the fastening elements, which are indicated by the numeral 15, are in the form of upwardly directed hooks uniformly spaced about the inner surface of the shield adjacent the lower edge thereof. The tent fabric is indicated by the numeral 16 and its upper edge may be provided with a plurality of doubled-over straps 17 providing anchors for complementary fastening elements 18 here indicated as metal loops or rings adapted to engage over the hooks 15.

From the foregoing description and the attached drawings, it will be apparent to those skilled in the art that I have provided a sturdy and durable construction of a stovepipe tent in which the stovepipe may be solidly located directly upon the ground or other foundation so as to firmly support a tent covering in an erect position, that the shield which is detachably

connected to the upper end of the stovepipe and functions to provide the connecting means between the upper edge of the tent fabric and the stovepipe also serves to space the tent fabric from the stovepipe thereby avoiding the possibility of igniting the former by heat passing through the pipe, and that the stovepipe is provided with a regulatable draft opening so situated as to be readily accessible and providing excellent draft for the stove which is connected to the stovepipe at a point spaced slightly above the draft opening.

In accordance with the patent status, I have described what I now consider to be the preferred form of the invention, but since various changes and modifications may be made in structural details without in any way departing from the spirit and scope of the invention, it is intended that all such changes be included within the scope of the appended claim.

I claim:

In combination, a base plate to be mounted on a floor or the like, a combined tent pole and stovepipe mounted on the base plate and extending upwardly therefrom, the lower portion of the combined tent pole and stovepipe provided with

10

a lateral opening at a height such as adapts it to receive a horizontal pipe connected to a stove mounted on the said floor or the like, said lower portion of the combined tent pole and stovepipe being provided with a draft opening disposed below said lateral opening, and a draft regulator for said draft opening.

EDWARD F. CAMPBELL.
